Patented Feb. 8, 1916.

Inventor:

Simon M. Frank,
by Hugh H. Wagner,
his Attorney.

UNITED STATES PATENT OFFICE.

SIMON M. FRANK, OF ST. LOUIS, MISSOURI.

NECKWEAR.

1,171,111.

Specification of Letters Patent.

Patented Feb. 8, 1916.

Application filed June 4, 1915. Serial No. 32,035.

To all whom it may concern:

Be it known that I, SIMON M. FRANK, a citizen of the United States, residing at the city of St. Louis and State of Missouri, have invented certain new and useful Improvements in Neckwear, of which the following is a specification.

This invention relates to neckwear, and specifically to neck-ties or scarfs or the like. 10 Particularly in open-ended scarfs having a lining in the neck-band thereof and extending outward toward the ends of the scarf, it has been found that the lining, when the scarf is used, will not lie flat, but wrinkles, 15 buckles, and "bunches up" in a way that makes it difficult to tie or to use the scarf and which causes it to impart an uncomfortable feeling to the wearer and which makes it impossible to tie it in a neat manner so 20 that the part forming the knot will lie flat and present the proper appearance.

The objection to ties in which the lining "bunches up" as aforesaid was not remediable by simply stitching through the tie and 25 thus tacking or catching the lining, because the presence of the stitching on the front or show-part of the tie would be even more objectionable and would render an article unsalable that was thus defaced. To prevent 30 such defacement, invisible stitching to bind the lining to the back only of the tie is a necessity.

As incidental to other features of construction of a lined open-ended scarf, others 35 have heretofore proposed longitudinal lines of invisible stitches adjacent to the respective lengthwise edges of the lining. This, nevertheless, permits wrinkling and buckling of the lining and more or less "bunching up" of the same between the longitudinal 40 lines of stitches. Moreover, as these lines of stitches are adjacent to the edges of the lining fabric, the stitching threads readily pull out free from the fabric and leave 45 the same loose and adapted to move about and fray and "bunch up".

The present invention has for its object an improvement of the foregoing by means of which movement of the lining and its 50 wrinkling, buckling, or "bunching up" will be precluded. This is accomplished by the use of invisible stitching spread about such an area and in such directions on the lining as to obviate the above-mentioned undesirable conditions. By "invisible stitching" 55 should be understood stitching that is in-

visible upon the show-part or front of the tie, the stitches being visible enough from the inner or back side of the tie.

In the accompanying drawings forming 60 part of this specification, in which like numbers of reference denote like parts wherever they occur, Figure 1 is a view showing a plan view of the two ends of the tie looking at the inner or back side thereof, portions of the tie material having been broken away to show a portion of the inner lining or filling; said Fig. 1 showing, also, a perspective view of the neck band of the tie; and Fig. 2 is a view in cross-section on the 70 line 2—2, Fig. 1.

The scarf is composed of ends 1 and neck band 2. Preferably extending through the neck-band and toward each of the ends is a piece of lining 3. This lining is preferably stitched by a blind-stitch machine, but may be stitched by an ordinary sewing machine, or by hand from the wrong side or the side of the tie that lies next to the person of the wearer, which stitches go through 80 only the said wrong side of the tie and the lining, but do not go through to the face or front of the tie, *i. e.*, the part that is shown or exposed to view when the tie is being worn. This stitching is adapted to tacking 85 down at a plurality of points transversely of the tie as well as along the length of the lining and may follow the course of a pair of relatively oppositely curved wave-like lines 4 undulated progressively from one 90 side to the other of the tie, each line crossing the other at intervals along the length of the tie, each corresponding pair of ends 5 of said lines 4 being spaced apart at opposite sides of an end of the tie, and there being a transverse line of stitching 6 adapted to traverse the distance between each of 95 said pairs of ends to cross-connect same adjacent to ends of said lining, substantially as shown in the accompanying drawing, the 100 terminal figures formed by said stitchings being substantially truncated double-convex-lens-shaped figures and the intermediate figures being a series of substantially double-convex-lens-shaped figures, and upon 105 the wider end of said tie the figures described by said stitchings may inclose areas progressively greater from a smaller area inclosed by the one of said figures adjacent the neck-band to the greatest area inclosed 110 by the truncated terminal figure on said wider end of the tie.

I claim:

- A necktie having neck band and tying end portions comprising a front portion and rearwardly-folded back portions, the edge 5 of each back portion being turned under to reinforce said edge, and a lining between the front and back portions, lines of stitches tacking said lining to said back portions and the turned-under edges thereof at a plurality of points transversely of the tie as well 10 as along the length of the lining, said stitches following the course of a pair of relatively oppositely-curved wavelike lines undulated progressively from one side of 15 the tie to the other, throughout the major portion of the tying end portions, each line

crossing the other at intervals along the length of the tie, each corresponding pair of ends of said lines of stitching being spaced apart at opposite sides of an end of the tie 20 and a transverse line of stitches traversing the distance between each pair of ends to cross-connect the same adjacent to the ends of the lining, said turned-under edges constituting a chord extending longitudinally 25 between the connecting wavelike lines at their points of intersection whereby tension on the necktie is neutralized through the area of the main part of the tie.

In testimony whereof I hereunto affix my 30 signature.

SIMON M. FRANK.
